[57] ABSTRACT

A safety gate held vertically in front of a press and a gate lift comprising a linkage system for moving the gate between a press exposing and a press blocking position. Spring means normally urge the lift into one of these positions, and a hydraulic motor or solenoid is connected to an initial link of the lift for normally urging the lift opposite thereto upon selective operation thereof.

SAFETY GATE FOR PRESS

BACKGROUND OF THE INVENTION

The present invention relates to safety devices for presses, rams and the like and, in particular, to an automatic gate for blocking entry to the interface of the dies of such machines.

It is known to provide a protective netting disposed in front of the press or ram for the purpose of protecting the worker against accidental casualty that may occur by the descent of the ram. Such known devices, however, are manually operable, requiring hand operation each time the press is raised and lowered. Furthermore, such devices are heavy. Consequently, the worker is inefficiently employed, tires easily and is not psychologically at ease.

The known devices are also uneconomical because they require large floorspace and complex operating mechanisms.

It is an object of this invention to provide a safety mechanism for a ram or press which overcomes the aforementioned disadvantages.

It is also an object to provide a safety mechanism which is automatically operable in conjunction with the ram movement.

It is a further object of the present invention to provide an inexpensive safety device for a ram or press.

It is another object to provide a safety device for a press or ram in which a gate blocks entry to the interface of the ram prior to the closure or full engagement of the ram.

It is a further object of the invention to provide a safety device for a ram or press which is operable in the event the ram or press accidentally falls.

It is still another object of the invention to provide a safety device which is operable automatically, at speeds greater than the operation of the ram or press.

Many more objects and advantages are obtainable from the present invention. These will be set forth in the following description.

SUMMARY OF THE INVENTION

In accordance with the present invention, a ram or press is provided with a movable gate means adapted to move automatically on actuation of the ram from a lower to a higher position in which the gate blocks the interface of the ram dies.

It is preferred that the mechanism move the gate in parallel relationship to the ground; that it be actuated rapidly and at least faster than the ram is moved; and that it be equally quickly returned to its free or starting position.

It is also preferred that the entire movement of the gate be accomplished in front of the ram apparatus so as to limit space use.

Still a further preference is that the gate and ram are interconnected so that the gate will provide ultimate safety in being actuated should the ram be accidentally lowered.

A full and detailed description of the present invention follows herein. The description makes reference to the appended drawing.

BRIEF DESCRIPTION OF DRAWING

FIG. 1 is front elevational view, in schematic representation, of a ram embodying the principle of the present invention;

FIG. 2 is a view similar to that of FIG. 1, showing the operative movement of the ram;

FIG. 3 is an enlarged perspective view of a portion of the device shown in FIGS. 1 and 2;

FIGS. 4-7 are serial views of the operation of the latch assembly of the device of FIG. 1;

FIG. 8 is a view similar to FIG. 1, showing a modification of the present invention;

FIG. 9 is a view similar to that of FIG. 8, showing still another modification;

FIG. 10 is a perspective view of a third modification;

FIGS. 11 and 12 are end views showing the operative stages of the modification of FIG. 10;

FIGS. 13-16 show still another embodiment in various end views;

FIG. 17 is a perspective view of another embodiment;

FIG. 18 is an end view of the embodiment of FIG. 17;

FIGS. 19 and 20 are schematic views of the crank detail of the embodiment of FIG. 17; and

FIGS. 21 to 23 show three embodiments respectively of the device shown in FIG. 17.

In all the figures, like numerals refer to like parts functioning in a like manner, thus avoiding redundancy in the description.

DETAILED DESCRIPTION

15 The present invention is embodied in a press or stamping machine of conventional design, comprising a flat bed or surface S resting on a base B supported by a plurality of legs. Mounted above the base B is a frame F supporting a vertically movable ram R which carries a die D adapted to engage with a mating die secured to the bed S. Between the interfaces of the dies, a workpiece may be pressed, stamped or otherwise manipulated.

20 For illustration only, a conventional mechanical press having an advancing worm W to which the ram R is coupled is shown. The motor drive, clutch mechanism, control means and the sundry other common features of presses of this type have been omitted for the sake of brevity. The present invention is equally adaptable to hydraulic or pneumatic presses, with little modification, as will appear to those skilled in this art.

25 The ram R is actuated by manipulation of a hand switch H and is caused to move downwardly with sufficient weight and force to manipulate a workpiece, such as a steel billet. The force necessary to do such work creates an inherently dangerous situation in which the worker or machine operator can be seriously, if not fatally, injured, simply by intruding himself or his limbs into the path of the ram.

30 The present invention provides a safety mechanism blocking the facade of the interface portion of the dies from accidental intrusion, comprising a gate G mounted on a reciprocating lift assembly A which is adapted to be moved between a low position clearing the die interface and an upper position blocking the interface. The lift assembly A is operatively connected to a latch assembly L which is directly operable in conjunction with the movement of the ram R to effect reciprocation of the gate in correspondence with the movement of the ram.

35 Turning to the details shown in FIG. 3 the latch assembly L comprises a solenoid coil 8 having a movable rod 9 which is normally depressed when the coil is not energized. The solenoid is located at the forward end of a mounting bracket 7 which is secured to the edge of the base B and which extends rearwardly along the side of the press. At the rear end of the mounting bracket 7 is a fan-shaped plate 10 freely pivoted at its apex about an axle 12. The plate 10 is provided with a plurality of openings 11 arcuately formed at the edge thereof at equal radii from the pivot 12. Connected to one of the openings 11 is a cable or connecting rod 13 which leads to an arm 15 which is itself connected to the operating clutch or worm W which effects the movement of the rod.

40 A plurality of openings 11 are provided in the plate 10 so that the cable 13 can be connected between it and the arm 15 in taut or tensioned condition, pivoting the plate 10 about the axle 12 counterclockwise (or upwardly), as seen in FIG. 7, when the ram R is in its most elevated position. Thus, as the ram R is lowered, the cable 13 slackens and the plate 10 drops or pivots clockwise, as seen in FIG. 5, and as the ram R thereafter again rises the plate 10 rises or pivots counter clockwise.

45 Mounted adjacent to the solenoid coil 8 at the forward end of the bracket 7 is an L-shaped lock member 16 freely pivoted at its elbow or joint. One arm of the lock 16 rests on the solenoid rod 9 which, when moved upwardly under excitation of

the solenoid coil 8, moves the lock 16 clockwise. The lock 16 is normally biased counter clockwise, or into engagement with the solenoid rod 9 by a spring 17. The end of the other arm of the lock 16 is provided with a cutout shoulder portion 18.

Pivotedly mounted about an axle 19 is an elongated lever 20 which at its forward end is adapted to engage beneath the shoulder 18 and at its rearward end with an arcuate hook 21 pivotally mounted on the fan plate 10. The hook 21 is provided with an adjustment screw 22 by which its movement may be limited.

The lift assembly, also seen in detail in FIG. 3, comprises a triangular crank 24 having a circular rod 23 extending from its apex into engagement beneath the lower edge of the lever 20 which forms part of the latch assembly L. The crank 24 is pivoted at its lower corner about an axle 26 and is biased by a tension spring 25 secured to the base B to be urged clockwise. A bar 27 is journaled to the upper corner of the crank 24 and extends laterally in front of the base B. The free end of the bar 27 is journaled to a link 28 which forms the first section of a multibar linkage by which the gate G is actually raised.

The multibar linkage comprises a shift bar 29, journaled to the end of the initial link 28, and which also extends across the front of the base B. An upwardly extending post 29a is fixed to the shift bar 29 at about its mid section. To the left of the post 29a and above the bar 29 there is located an intermediate bar 32 which has a triangular end 30a one corner of which is journaled to the center 30 of the link 28, and the other corner of which is journaled to a third bar 31. The third bar 31 extends generally parallel to the bar 29 and is itself journaled to the post 29a. To the right of the post 29a and opposed to the bar 32 is a second intermediate bar 34 which has an angular end 34a journaled to the right most end of the lower rod 29 and pivoted at 33 with respect to the base B. The free ends of both intermediate bars 32 and 34 extend toward each other at the post 29a and are respectively journaled to angularly upwardly extending arms 36 and 37, which are themselves pivotally connected to a mounting plate 35.

It will thus be observed that, if the bar 27 is moved to the right, the shift bar 29 moves leftward, causing the intermediate bar 32 to move counterclockwise about the axis of its pivot 30 and the opposing bar 34 to move clockwise about the axis of its pivot 33. In doing so, the bars 36 and 37 are distended, raising the mount 35, as clearly seen in FIG. 2. When the bar 27 is moved to the left, the opposite movement occurs and the mount 35 is lowered. To insure vertical movement, the mount 35 is provided with a depending rod 38 which fits into a guide passage in the base B. The bar linkage is normally maintained in a closed position or in a position where the mount is lowered because, in inoperative condition of the press, the lever 20 causes the rod 23 of the crank 24 to be held in its most counterclockwise position, holding the shift bar 29 cocked to the right. A spring 39, having one end connected to the base B and the other end to the extreme right end of bar 29, constantly urges the bar 29 leftward, insuring operation of the lift assembly immediately upon release of the lever 20 from engagement with the latch hook 18.

A pair of angle brackets 40 are mounted on the edge of the mount 35. Each bracket has a hole adapted to receive a rod 40a depending from the gate G. The height of the gate G may be varied by providing either rod 40a or bracket 40 with an adjustment screw or other similar means for clamping the rod and bracket at various positions so that the gate may be selectively located in association with the dies of differing interface height. The gate G and rods 40a may also be adjustably mounted to vary the lateral position of the gate crosswise with respect to the die interface.

The gate G is a flat rectangular plate preferably made of transparent plastic so that the operator will be able to observe the work in progress during operation of the machine. The gate may, however, be of metal, rubber or sheet material of any suitable thickness and strength for the intended purpose of preventing intrusion into the interface of the die.

In operation, a workpiece is placed on the lower die and the switch H is momentarily closed, producing an electric current which simultaneously energizes the ram clutch or motor mechanism and the solenoid coil 8 of the latch assembly. At 5 this time, the situation is as is seen in FIGS. 1, 3 and 4 where the lift assembly is held in its downward position because the crank 24 is held under the lever 20 which is hooked under the latch 16. On excitation of coil 8, the rod 9 moves upwardly, rotating the L-shaped latch 16 clockwise, which releases the lever 20 (FIG. 5), causing the crank 24 to pivot immediately under the action of both springs 25 and 39 and shifting the bar 29 leftward, as viewed in FIG. 3. As a result, the opposed bars 32 and 34 move symmetrically in opposite directions so that the bars 36 and 37 move upwardly, carrying the mount 35 and the gate G attached thereto, as seen in FIG. 2. The movement of the lift assembly is similar to the operation of a scissor-type bar linkage, in which the mount 35 and gate G always maintains a purely horizontal or parallel movement to the ground or shift bar 29.

20 The present arrangement enables the gate G to be elevated quickly and, in fact, before the ram R itself is fully lowered. This results from the scissor type lift assembly in which all elements perform their intended function simultaneously and not serially. Thus, as soon as the latch L is released, the gate G begins its ascent, providing a substantial advantage in safety.

In the meantime, the actuation of switch H causes the clutch to drive the ram R downward, slackening the cable 13 and allowing the fan plate 10 to fall freely, as seen in FIG. 5. When 30 the fan plate 10 drops to its lowest position, the hook 21 falls beneath the rear end of lever 20 which is tilted downwardly because of the clockwise movement of crank 24. After the ram R has reached its lowest position and has finished manipulating the workpiece, it begins an automatic rise upwards. The 35 rising ram gradually pulls the cable 13 taut, raising the fan plate 10 about its pivot. As the fan plate 10 thus moves, the hook 21 engages the rearward end of the lever 20, causing it to rotate counterclockwise. The lever 20 presses against the rod 23 of the crank 24 and rotates the crank 24 counterclockwise 40 also.

The counterclockwise movement of the crank 24 causes the shift bar 29 to move to the right against the action of springs 25 and 39, collapsing the entire lift assembly and lowering the gate from the facade of the die interface. When the lift assembly is fully collapsed, the forward end of the lever 20 hooks under the shoulder 18 of the latch 16, as seen in FIG. 6, locking the lift assembly in closed position. The ram, however, is adapted to continue further upward, carrying the fan plate 10 still further so that the hook 21 disengages from the rear 50 end of lever 20, as seen in FIG. 7, and the apparatus returns to its original portion.

The present invention may be adapted in many forms. For example, it may be desired to move the gate G downwardly rather than upwardly into position before the facade of the interface of the dies. Such a situation is shown in FIG. 8, and is easily effected by simply journaling the working bar 27 to the lower corner of the crank 24 rather than to the upper corner, as shown in the embodiment of FIGS. 1 to 7. Thus, in FIG. 8, 55 when the lift assembly is normally maintained open and when the crank 24 is rotated in its normal clockwise direction, the assembly and gate G are lowered rather than raised. The operation of the latch assembly L is the same as previously described even though the operation of the lift assembly is reversed. All parts are otherwise also the same.

60 Another embodiment is seen in FIG. 9, wherein the apparatus is shown without a latch assembly L. In its place, a hydraulic or pneumatic motor comprising a pump 41 and a piston 42 is provided. The outer end of the piston 42 is coupled directly to the working bar 27 by a suitable fitting 43 which may simply be a right-angle bracket. The working bar 27 is also directly journaled to the vertical post 29a, the crank 24 and spring 25 being omitted, although the link 28 is retained. An elongated spring 44 is mounted across the front 75 of the base B, having one end secured thereto and another end

secured to the shift bar 29. Thus, the shift bar is normally biased to the left urging the lift assembly A open. However, the pump 41 maintains the assembly closed by pulling the working bar leftward, at the same time overcoming the bias of the spring 44. During operation, the pump 41 urges the piston 42 to the left, under actuation by switch H, thus causing the working bar 27 to move to the left, the shift bar 29 to the left, and the assembly to rise. It is noted here that actual mechanical coupling to the ram R is avoided.

The reverse procedure occurs in downward movement. As in the second mentioned embodiment, all other parts are the same in both form and function.

FIG. 9 illustrates still another modification relating to the form of the gate supports on the mount 35. In this modification angular or bent supports 45 are provided which enable the gate G to be positioned closer to the working position. This is desirable when the apparatus is employed to block or hide a mold rather than a press.

FIGS. 10 to 12 show a fourth embodiment wherein the gate G is operated electrically. Located alongside of the press is a housing 47 containing a first electromagnet or solenoid 48 and a second electromagnet or solenoid 49. Associated with the two magnets is a rod 51 journaled about its center to a shift 50 and secured at each end to a movable magnetic core 52 and 53, respectively. The solenoids 48 and 49 are adapted to reciprocate the cores 52 and 53 vertically, alternately moving the rod 51 in see-saw fashion.

Extending vertically at the front of housing 47 is an upright standard 54 having secured thereto several sets of parallel links 55a and 55b. Each of the links 55a and 55b comprises at least two double pairs of rods which are angularly coupled in pantograph fashion. A pushrod 56 extends from the magnet core 53 to the lowermost set 55a. A rod 57 extends rearwardly from this same set to connect with one of the sets 55b disposed angularly to it. Thus, as the magnetic cores 52 and 53 are reciprocated, the pantograph structure is raised and lowered.

At the forward end of the pantograph's upper link set 55b a post 58 is pivotally secured, on which is also mounted the gate mount 35. An elastic strip of material is bonded to the upper edge of mount 35. The gate G may thus be pinned or otherwise draped over the mount as seen in FIG. 12. Lastly, a spring 60 is connected between the standard 54 and the pushup bar 57 to assist in the upward movement of the pantograph.

Suitable switch means and electrical controls are provided although not shown in the drawings whereby, when the ram is operated, a simultaneous electric signal is transmitted to magnet 48 which depresses the core 52, raising the push rod 56 and operating the pantograph arrangement to raise the gate G. When the ram has completed its operation, a suitable limit switch is again activated, this time supplying electricity to the second magnet 49 which pulls the core 53 and push rod 56 downwardly, collapsing the pantograph.

In FIGS. 13 to 16, still another embodiment is shown, in which the latch assembly features of the preferred embodiment of FIGS. 1 to 7 is combined with the pantograph features of the preceding embodiment. In this construction, all of the features of the two systems remain the same, except that the pushrod 56 is elongated and is connected to the lever 20 so as to be directly operated by it. Here, the upward movement of the pantograph is accomplished solely by the strength of the spring 60, after the lever 20 is released from the latch 16. The downward movement of the pantograph is effected by the tensioning of cable 13 which causes hook 21 to pivot the lever 20, as previously explained, to pull, in this case, the push rod 56 downwardly, collapsing the pantograph. All other structures and functions remain the same as previously described.

FIGS. 13-16 also illustrate another feature. The upper sets of parallel bars 55b may be made laterally wider than the lower sets 55a so that the pantograph may be made to move over the center, as seen in FIG. 13, with the upper sets 55b moving below the lower sets to carry the gate G to a lower position than in the previous embodiments.

While the embodiments shown hereinbefore are advantageous and beneficial, certain machines and applications do not provide the space necessary for the scissor or pantograph lift assemblies. Additionally, it may be desirable to position the gate G closer to the die or mold than even those embodiments provide. It may also be desired to provide a less expensive and simpler apparatus for smaller presses.

Accordingly, in FIGS. 17 to 23, there are shown still further embodiments of the present invention.

Referring first to FIGS. 17 and 18, the apparatus is applied to a press similar to that described earlier, comprising schematically a base B, a frame F on which is mounted a ram R provided with a die D. A lower mating die D' rests upon the beds of the base B. As in the prior embodiment, the ram is preferably mechanically driven by a worm and clutch assembly. To avoid repetitive descriptions and illustrations, many parts have not be shown again or described. Those shown bear the same reference numerals. Those not shown will be understood to have been included by reference.

The embodiment of FIGS. 17-20 comprise a bracket 103 secured to the base and extending outwardly to the side, on which is mounted a bifurcated vertical standard 104. Between the bifurcated standard 104 are pivotally secured an upper and lower pivot block 105a and 105b. Secured to each of the blocks 105a and 105b, along their respective longitudinal axes, are rods 106a and 106b. The vertical standard 104 is positioned so that the rods 106a and 106b extend toward the lower die D' or at least to a frontal position adjacent its facade. Attached by pivots 107a and 107b to the ends of the rods 106a and 106b, is a gate G similar to that previously described. The pivots 107a and 107b are spaced apart a distance equal to the distance between pivot blocks 105a and 105b to provide a parallel four-bar linkage by which pivoting of either of the blocks 105a or 105b raises the gate G vertically while maintaining horizontal relationship to ground.

The lengthwise position of the rods 106a and 106b may be adjusted by providing screw fasteners 108 in association with the pivot blocks 105a and 105b (FIG. 18).

Mounted on the standard 104 is a pneumatic motor 109, comprising an air cylinder 110 and a piston 111. The piston 111 is secured by a journal 112 to the upper block 105a, and is movable upwardly by entry of air into the cylinder 110 through a hose 113. The hose 113 is connected to a conventional source of air under pressure, such as a pump (not shown), which is actuated by the machine operating switch H.

Behind the standard 104, as seen in FIG. 17, there is located a spring 114, one end of which is connected to the standard 104, the other end of which is connected to the lower rod 105b so that, on release of air from the cylinder 110, the parallel assembly may be quickly lowered.

Pivotedly coupled to the bottom edge of the lower pivot block 105b is a lever arm 115 which extends outward of the bifurcated standard 104 and rests on a stop 116 secured thereto. A compression spring 117 is also employed between the pivot block 105a and the arm 115 to move the lever arm 115 on the movement of lower rod 106b, opening or closing the switch 119. A contact cap 118 is rotatably secured to the outer end of the arm 115 and has a triangular shape, as more clearly seen in FIG. 18. Below the arm 115 is located a microswitch 119 which, when closed, controls the ram drive and clutch mechanism.

Thus, when the gate G rises under action of the pneumatic motor, the lever 115 moves counterclockwise, causing the contact cap 118 to fall and close switch 119 operating the ram R. This is advantageous in that the control switch H does not operate the ram directly, but only indirectly after actuation of the safety gate G is initiated. On downward movement, the reverse operation occurs. Firstly, the downward movement of the gate G causes the lever 115 to move clockwise, raising the contact cap 118 and opening the ram control circuit. The ram is thus raised before the gate is fully removed. The rotatable cap insures free movement of lever 115 relative to the switch.

Mounted on the upper edge of the standard 104 are a pair of screws 104a which are adjustable to vary engagement with the upper pivot block 105a, thus limiting the movement of the block and the rods 107a and 107b.

The embodiment shown in FIGS. 17 and 18 permits of further advantageous modification, as seen with regard to FIGS. 19 and 20. As noted, the ram R is mechanically driven so that a crank shaft 120 or other drive shaft is provided. It is, of course, movable conjointly with the ram and will move should the ram accidentally fall. The crank shaft 120 rotates eccentrically in known manner about a central axis 121 (FIG. 20) in the direction of arrow 122.

Mounted above the crank shaft 120 in a position slightly deviated past dead center, in the rotating direction of the crank, is a microswitch 123. Mounted below the crank in a position slightly deviated forwardly of the dead center position is a second microswitch 124. The upper microswitch 124 is so arranged that it is energized on rotation of the crank, and placed in the circuit controlling the air pump in parallel with the switch H so that it will operate the pump even though switch H is not closed. This provides an added measure of safety in that, should the ram accidentally begin to fall for any reason, the gate G will be immediately raised, protecting the worker.

The lower switch 124 is arranged to be energized when the ram has reached its lowest position (i.e., the dies engage). The switch 124 is also placed in the circuit of the pneumatic pump but is adapted to stop the pump, relieving the pressure in cylinder 110 and thus allowing the gate G to fall free as the dies meet and it is safe to open the facade.

The microswitch, of course, may be located at other positions and arranged in the operating circuits in other ways to achieve the same result.

Operatively, a workpiece is first placed on the lower die D1 and the starting switch H is closed, supplying air to the cylinder 110 and forcing the piston 111 upwardly. The upward movement of the piston rod 111 is transmitted through fitting 112 to the pivot blocks 105a and 105b, rotating them counter clockwise until they abut against the screws 104a. The gate G is thus raised to block the die interface. As this occurs, the ram 115 falls and causes the cap 118 to energize the switch 119, permitting the ram to move downwardly. As soon as the ram completes its downward movement, the switch 124 is closed, causing the pneumatic pump to depressurize and raising the gate G. This is advantageous, since it permits the worker to have access to the machine immediately upon removal of any dangerous situation. Time need not be lost waiting for the ram to rise before access can be had to the die.

Since the switch 123 is offset from dead center, the ram can return to its uppermost position and remain there without causing repetitive operation of the gate. However, should it happen that the ram falls accidentally, the switch 123 will immediately cause the raising of the gate.

While a pneumatic motor 109 is shown, electromagnetic drive means similar to that shown previously may be employed, as is shown in FIG. 21. A magnet 125 having a core 126 connected to the lower pivot block 105b is arranged on the bracket 103. In this instance, it may be desirable to place the microswitch 119 above the block 105b so that its actuating arm falls freely. The actuation of the microswitch 119 may thus be simply effected by a tab 127 extending outwardly from the block 105b. The magnet core is adapted to move downwardly on energization by switch H, raising the gate G as previously described.

In FIG. 22 still another embodiment is shown. This embodiment combines the features of a latch assembly shown in FIGS. 1-7 with the parallel-type gate arrangement shown in FIGS. 17-20. Here, the lower pivot bar 105b is linked by a vertical bracket 130 to a pivotal lever 131 journaled to bracket 103. The lever 131 is adapted to hook under a latch 132 pivoted by a solenoid 133. The rear end of the lever 131 is adapted to be raised by a hook 134 secured to a fan plate 135 pivoted about an axle 136 under actuation by a cable 137, all in the manner earlier described in connection with FIGS. 1-7.

As previously explained, the upward movement of the ram causes the hook 134 to pivot the lever 131 into latched engagement under the end of latch 132. Simultaneously it pulls down the bracket 130 and pivot block 105b which causes the gate G to move downwardly out of blocking position. However, on actuation of the switch H, the latch 133 is released and the spring 114 causes the gate to rise immediately. The microswitch 119 and contact 118 are arranged so that, after the gate moves upwardly, the switch 119 is energized, permitting downward movement of the ram.

Still another embodiment is shown in FIG. 23 where a reversible motor 140 coupled to a reducing gear means 141 is substituted for the magnet and core of FIG. 21. The gear mechanism 141 drives a rotary arm 142 at predetermined speed to move an arm 143 coupled to the pivot block 105b. Otherwise the structure and operation is the same as described in connection with FIG. 21.

Since various modifications and embodiments have been shown and various others will be readily apparent to those skilled in this art, the present specification is to be taken as illustrative only of the invention disclosed.

What is claimed is:

1. Safety apparatus for a press or the like having a base, a ram disposed above said base and mounted to reciprocate vertically with respect thereto, means selectively operating said ram to move up or down, said base and ram each carrying mating dies for manipulating a workpiece placed therebetween on the downward movement of said ram and engagement of said dies, said apparatus comprising a gate, support means for holding said gate vertically in front of said press, a lift assembly comprising a plurality of interconnected links for moving said gate from a first position exposing said engaging dies to a second position blocking said dies, spring means for urging said lift assembly normally into one of said positions, reciprocating motive means consisting of a fluid operated piston and cylinder connected to the initial link of said lift assembly and arranged to normally urge said lift assembly opposite thereto, and means for selectively operating said motive means to effect movement of said lift assembly from one position to the other.

2. The apparatus according to claim 1, wherein said links maintain said gate in parallel arrangement to ground during movement between said first and second positions.

3. Safety apparatus for a press or the like having a base, a ram disposed above said base and mounted to reciprocate vertically with respect thereto, means selectively operating said ram to move up or down, said base and ram each carrying mating dies for manipulating a workpiece placed therebetween on the downward movement of said ram and engagement of said dies, said apparatus comprising a gate, a support for holding said gate vertically in front of said press, a lift assembly comprising a plurality of interconnected links for moving said gate from a first position exposing said engaging dies to a second position blocking said dies, reciprocating motive means connected to the initial link of said lift assembly, means for selectively actuating said motive means to effect movement of said lift assembly from one position to another, switch means associated with said lift assembly and energizable on movement thereof from said first position to said second position to actuate said ram whereby said gate is positioned prior to engagement of said dies, said switch means being operable to return said gate to said first position prior to the return of said ram.

4. The apparatus according to claim 3, wherein said motive means comprises a fluid piston and cylinder.

5. The apparatus according to claim 3, wherein said motive means comprise a reversible motor.

6. The apparatus according to claim 3, wherein said motive means comprises a solenoid.

7. The apparatus according to claim 3, including circuit means associated with said ram to actuate the link assembly motive means on downward movement of said ram independently of said switch means.

8. The apparatus according to claim 7, wherein said circuit means includes a switch associated with the ram drive and operable on movement of said drive to energize the motive means.

9. Safety apparatus for a press or the like having a base, a ram disposed above said base and mounted to reciprocate vertically with respect thereto, means selectively operating said ram to move up or down, said base and ram each carrying mating dies for manipulating a workpiece placed therebetween on the downward movement of said ram and engagement of said dies, said apparatus comprising a gate, sup-

port means for holding said gate vertically in front of said press, a lift assembly comprising a plurality of interconnected links for moving said gate from a first position exposing said engaging dies to a second position blocking said dies, spring means for urging said lift assembly normally into one of said positions, reciprocating solenoid means connected to the initial link of said lift assembly and arranged normally to urge said lift assembly opposite thereto, and means for selectively operating said solenoid means to effect movement of said lift assembly from one position to the other.
